(57) **CLAIM**

The ornamental design for a journal cover, as shown and described.

DESCRIPTION

FIG. 1 is a front and top perspective view of a journal cover showing my new design;

FIG. 2 is a rear and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view thereof in an open position; and, FIG. 10 is a front view of the journal cover in an alternate configuration.

The broken lines depict environment and form no part of the claimed design.

1 Claim, 10 Drawing Sheets(56)
